UNITED STATES PATENT OFFICE.

JOSEPH M. CONNELLY, OF PHILADELPHIA, PENNSYLVANIA.

COLLAPSIBLE WARDROBE.

1,072,089.

Specification of Letters Patent.

Patented Sept. 2, 1913.

Application filed March 8, 1912. Serial No. 752,804.

To all whom it may concern:

Be it known that I, JOSEPH M. CONNELLY, a citizen of the United States, residing at Philadelphia, in the county of Philadelphia and State of Pennsylvania, have invented certain new and useful Improvements in Collapsible Wardrobes, of which the following is a specification.

My invention relates to improvements in collapsible wardrobes, the object of the invention being to provide a device of this character which will support a number of articles of clothing, yet which may be collapsed and readily carried in a suit case or trunk.

A further object is to provide a collapsible wardrobe which comprises arms and legs connected by a telescoping standard, the latter adapted to receive the arms and legs therein when collapsed so that the device will occupy but relatively small space when not in use.

A further object is to provide a wardrobe of this character together with an improved flexible casing which may be removed and replaced as desired.

With these and other objects in view, the invention consists in certain novel features of construction and combinations and arrangements of parts as will be more fully hereinafter described and pointed out in the claims.

In the accompanying drawings: Figure 1 is a view in elevation illustrating my improvements showing the casing partly broken away at the top and illustrating the front flaps of the casing partially opened to disclose the interior of the wardrobe. Fig. 2 is a view in longitudinal section through the casing. Fig. 3 is a plan view of the casing frame. Fig. 4 is a broken view in longitudinal section illustrating the collapsible clothes support in operative position. Fig. 5 is a similar view showing the clothes support folded and collapsed. Fig. 6 is a view in section on an enlarged scale on the line 6-6 of Fig. 4, and Fig. 7 is a view in side elevation of the leg holding plate 10.

1 represents a tubular telescoping standard supported by tubular telescoping legs 2 at its lower end and provided at its upper end with two aligned article supporting tubular telescoping arms 3, 3. The telescoping sections of standard 1, legs 2, and arms 3 are provided with set screws 4 to secure the same at any longitudinal adjustment. The

legs 2 project through openings 5 in a cap 6 which constitutes a casting and secured on the lower end of standard 1. This cap 6 has a conical central block 7 against the inner end of which a block 8 is secured by a screw 9. The inner ends of the legs 2 lie against the sides of block 7 and bear against the beveled side edges of block 8 when the legs are in operative position as indicated in Fig. 4. To hold them in this position, a locking plate 10 is provided which is somewhat of the shape of a Maltese cross and has rotary mounting upon a screw 11 projected through a central opening in plate 10 and screwed into block 7. Finger holds 12 are provided on plate 10, so that the latter may be turned, so that its ends bear against legs 2 and hold them at the angle indicated in Fig. 4. This position of the plate is shown clearly in Fig. 5.

When it is desired to collapse the device, the plate 10 is turned so that its ends are located between the several legs and the latter may be swung to a position in line with the standard, and then forced up into the standard as indicated in Fig. 7. The arms 3 are supported in collars 13 which have hinge connection 14 with a ring 15, the latter secured on the upper end of standard 1. A plug 16 projects into one arm 3 and is secured therein by a cross pin 17. This plug 16 also projects into the other arm 3 when the arms are in alinement as shown in Fig. 4, and holds the arms in this position. When it is desired to collapse the arms, they are moved longitudinally away from each other to draw the plug 16 out of the right hand arm 3, when both arms may be swung into parallelism by reason of the hinged connection 14, and then both arms may be forced through the sleeves 13 down into standard 1 as indicated in Fig. 7. It will thus be seen that both arms and legs may be moved inside the tubular telescoping standard 1, and this standard may be shortened so that the device will occupy but very small space and can be readily packed in a trunk or traveling bag. In connection with this support, I provide a flexible casing 18 which is held in rectangular formation by a telescoping frame 19 indicated most clearly in Fig. 3. The casing 18 may be made of any suitable flexible material with a dome-like upper end 20 which has a central reinforced opening 21 positioned over a knob or button 22 on the upper end of a post 23. This post 23 is adapt-

ed to be screwed into a threaded socket 24 in plug 16, and the sides of the casing extend preferably in proximity to the floor so as to exclude dust and dirt.

5 The front of the casing comprises two curtains 25 which are adapted to be connected by snap buttons 26 or other suitable devices, and at their upper ends are connected to rings 27 which slide on the front member of frame 19. An overlapping flap 28 is provided on the dome-like top 20 of the casing to cover the rings 27 and the upper ends of curtains 25, and give to the casing a neat and attractive appearance.

10 15 It will be noted that with my improvements, the casing may be readily disconnected from the article supporting frame and folded into small space so that when the article supporting frame is collapsed and the 20 parts telescoped, the entire wardrobe may be packed in a suit case or trunk and readily carried from place to place.

15 The device may be readily set up by any one of average intelligence, and by employing any suitable form of hooks 29 on the arms 3, a large number of articles of clothing may be supported thereon.

20 25 Various slight changes might be made in the general form and arrangement of parts described without departing from my invention, and hence I do not limit myself to the precise details set forth, but consider myself at liberty to make such changes and alterations as fairly fall within the spirit 30 and scope of the appended claims.

35 Having thus described my invention, what I claim as new and desire to secure by Letters Patent is:

1. A device of the character described, 40 comprising a tubular standard, two collars hinged to the end of the standard and located at opposite sides thereof, said collars adapted to be positioned in alinement or be swung to a position over the tubular stand-

45 ard, tubular arms in said collars adapted to be positioned at right angles to the standard or be moved into the standard, and means holding said arms in alinement with each other, substantially as described.

50 2. A device of the character described, comprising a tubular standard, two collars hinged to the end of the standard and lo-

cated at opposite sides thereof, said collars adapted to be positioned in alinement or be swung to a position over the tubular standard, tubular arms in said collars adapted to be positioned at right angles to the standard or be moved into the standard, a plug fixed in one arm and adapted to be projected into the other arm, coupling said arms and holding the collars against pivotal movement, substantially as described. 55

3. A device of the character described, comprising a tubular standard, two collars hinged to the end of the standard and located at opposite sides thereof, said collars adapted to be positioned in alinement or be swung to a position over the tubular standard, tubular arms in said collars adapted to be positioned at right angles to the standard or be moved into the standard, a plug fixed in one arm and adapted to be projected into the other arm, coupling said arms and holding the collars against pivotal movement, and legs supporting the lower end of said 70 standard and adapted to be moved inside the standard, substantially as described. 75

4. A device of the character described, comprising a tubular standard, collars having hinged connection to the upper end of the standard at opposite sides thereof, tubular arms in said collars, and a plug secured in one arm and projected into the other, substantially as described. 80

5. A device of the character described, comprising a tubular standard, collars having hinged connection to the upper end of the standard at opposite sides thereof, tubular arms in said collars, a plug secured in one arm and projected into the other, 90 said arms comprising a plurality of tubular telescoping sections adapted to be moved into the standard when the plug is withdrawn and the collars swung on their hinges to move the arms in parallelism, substantially as described. 95

In testimony whereof I have signed my name to this specification in the presence of two subscribing witnesses.

JOSEPH M. CONNELLY.
